UNITED STATES PATENT OFFICE.

WILLIAM L. PIKE, OF GROTON, NEW YORK.

DESIGN FOR A CARRIAGE-BODY.

SPECIFICATION forming part of Design No. 26,873, dated April 6, 1897.

Application filed February 5, 1897. Serial No. 622,225. Term of patent 7 years.

To all whom it may concern:

Be it known that I, WILLIAM L. PIKE, a citizen of the United States, residing at Groton, in the county of Tompkins and State of New York, have invented and produced a new and original Design for a Carriage-Body, of which the following is a specification, reference being had to the accompanying drawings, forming a part thereof.

10 The nature of my design is fully represented in the accompanying drawings, in which—

Figure 1 is a side view of my design for a carriage-body. Fig. 2 is an under view of the same, and Fig. 3 is a front end view.

15 The box A or main portion of the body is curved from the top downward at the rear end, as seen at B. The lower portion of said box is then extended in a straight line and then gradually curved upward to the front 20 end C. Upon the front end is mounted the dashboard D, comprising the panels d and tapered side wings d', having rounded top portion rising above the panels. A rail d², of like contour, is mounted above the dashboard, and 25 a second rail d³, having its ends coiled, surrounds the whole.

The upper contour of said body, beginning at the front end C, follows very nearly the curve of the lower front portion of the body 30 until it approaches the box portion A, where it curves sharply upward until it meets the top line of the box and thence it continues in a straight line to the rear end B.

35 The heavy lines B' in the side of Fig. 2 indicate the contour of the door E, which is

hinged therein at its vertical side e' and is wider at the top than at the bottom. The contour of the door is more distinctly shown in Fig. 1, where it is seen in opened position resting against the side of the box.

40 A frame a, comprising the rails a' and posts a² and having rounded ends, surmounts the top of the box A, and ornamental curved figures a³ are seen on the top of the frame at each end.

45 Projecting rearwardly from the bottom of the box is the curved end-board F, as seen in Fig. 2, where it is shown in open position, as when the surrey is used as a trap with the rear seat placed back to back with the front seat.

50 The upper side portions of the box A have a narrow longitudinal panel b of latticed work extending its full length, and below it is a second panel b' of similar character, but which is wider and of finer mesh, which also 55 extends across the side of the box A.

Having thus described my invention, what I claim as new, and desire to secure by Letters Patent, is—

56 The design for a wagon-body, substantially as shown and described.

In testimony that I claim the foregoing as my invention I have signed my name, in presence of two witnesses, this 4th day of February, 1897.

WILLIAM L. PIKE.

Witnesses:

C. SEDGWICK,
B. McCOMB.
